UNITED STATES PATENT OFFICE.

FRANK A. HOILES, OF ALLIANCE, OHIO.

BRICK-ORNAMENTING DEVICE.

1,185,800.

Specification of Letters Patent. Patented June 6, 1916.

Application filed October 10, 1914. Serial No. 865,991.

To all whom it may concern:

Be it known that I, FRANK A. HOILES, a citizen of the United States, residing at Alliance, in the county of Stark and State 5 of Ohio, have invented a new and useful Brick-Ornamenting Device, of which the following is a specification.

This invention relates to improvement in brick ornamenting devices and has more 10 especial reference to a device of that character which is used in coöperation with a brick machine which employs what is known as the stiff mud process of making brick by which a column of clay is formed in a die 15 and carried away upon an endless conveyer to a brick cut-off table which cuts the clay column into brick of the proper size.

The object of this invention is to provide 20 means adapted to act upon the top and side faces of the clay column for the purpose of producing an ornamental textile effect similar to a rug or carpet upon said faces. After 25 the clay column is carried to the cut-off table and cut into the brick of the proper size each brick will be ornamented upon its face and ends with this textile appearance.

A further object is to provide a device of 30 the character referred to in which a rotary device is employed for the purpose of tearing up a thin layer from a face of the clay column, grating or shredding the material 35 thus removed from the surfaces of the column and depositing the same again upon the face of the column, from which it was 40 removed, equally distributing the shredded portions of the clay thus removed.

A still further object is to provide in co-operation with a rotary device as above described, means for causing the shredded or 45 grated material to again adhere to the clay column, giving the proper textile effect.

With these objects in view the invention 50 consists in the novel construction and arrangement of parts, hereinafter described, 55 illustrated in the accompanying drawings, and particularly pointed out in the appended claims, it being understood that various changes in the form, proportions, size 60 and minor details of construction may be 65 made within the scope of the appended claims without departing from the spirit or sacrificing any of the advantages of the invention.

In the drawings: Figure 1 is a side elevation 70 of a device constructed in accordance with my invention, parts being broken

away for the purpose of illustration. Fig. 2 is a top plan view of the same with some of the parts shown in section. Fig. 3 is an enlarged sectional view through the rotary 60 cutter. Fig. 4 is a detailed perspective view of one of the spades which is carried by the rotary cutter. Fig. 5 is a similar view of a slightly modified form of spade. Fig. 6 is a horizontal sectional view through 65 one of the brackets and bearing blocks. Fig. 7 is a fragmentary view of one of the finished brick formed with this device.

Similar numerals of reference indicate 70 corresponding parts throughout the several figures of the drawing.

In the present method of forming brick having a textile appearance the face of the clay column is first acted upon by the rotary cutter which removes the greater part 75 of the material from the face of the column and shreds or grates the same after which it is deposited again upon the face of the column from which it has been removed. In order to cause the particles of clay thus 80 deposited upon the clay column to adhere thereto a fine jet of steam is directed upon the face of the column after which the column passes beneath drying rolls and for further drying the clay electric fans are 85 used as shown at 42, Fig. 1. By this process the particles of clay which have been removed and again deposited upon the face of the clay column will be caused to firmly 90 adhere thereto.

More specifically describing the mechanism illustrated in the accompanying drawing the numeral 1 indicates a die such as is ordinarily used upon brick machines 95 of that character which employ a stiff mud process and 2 indicates a portion of the brick machine. These parts are of the ordinary construction, well known to those skilled in the art and need no further mention here. A clay column is shown issuing 100 from the die and is designated by the letter A.

Side frames 3 and 4 are supported upon the die to which they are attached by means of bolts 5 or their equivalents. Brackets 6 105 are carried upon the frames 3 and 4 and bearing blocks 7 are slidably mounted upon said brackets, each of said bearing blocks being provided with a slot 8 through which a screw 9 is passed, said screw engaging a 110 suitable screw threaded socket 10 in the bracket for the purpose of rigidly holding

the bearing block in the proper vertical adjustment. A set screw 11 is provided for adjusting the vertical position of the bearing block. A shaft 12, preferably provided with 5 a central squared portion 13, is journaled in the bearing block 7 and is provided upon one extremity with a drive pulley 14, to which a suitable belt attached to any source of power may be attached. Teeth are provided upon 10 the shaft 12, said teeth being preferably passed through apertures 15 in the squared portion of the shaft and held in position therein by means of set screws 16. It is preferable to arrange two oppositely disposed staggered rows of these teeth, one row being made up of teeth having blades which we term spades, said spades being designated by the numeral 17, the opposite row being made up of sharpened, pointed teeth 18. Of 15 course, if desired all of the teeth could be of the form provided with sharpened points such as designated by the numeral 18 or if desired they could all be of the spade type, but with the arrangement above referred to 20 it has been found by experience that a more desirable result may be obtained. It will be noticed that the teeth terminate a short distance inside of the longitudinal corners of 25 the clay column in order to prevent the corners of the clay column from being torn away. If the face of the clay column was 30 not acted upon by some other cutting mechanism after the column had passed beneath the rotary cutter just described, it is obvious 35 that a blank marginal space would be left along each corner of the column and although in the production of some bricks it may be desirable to have such a blank space the general demand is for a brick, the entire 40 face of which will present a uniform appearance and for this purpose I provide additional rotary cutters which are adapted to treat the face of the column adjacent to the longitudinal corners thereof in the same 45 manner that the entire face of the column is treated.

A shaft 19, similar to the shaft 12 is located at an angle to the shaft 12 and is mounted in suitable bearing blocks 20, which 50 are adjustably mounted upon brackets 21 similar to the brackets 6, these brackets being carried upon the frames 3 and 4. The shaft 19 is provided with the squared portion 22 and carries two staggered rows of 55 teeth, the sharp pointed teeth such as designated by the numeral 18 being found preferable. A driving pulley 23 is provided upon one extremity of the shaft 19 and is adapted to be driven by a suitable belt in the direction shown by the arrow thereon. It will be 60 noticed that the teeth upon the left extremity of the shaft 19 terminate short of the longitudinal corner of the column while the teeth at the right extremity of the shaft extend 65 beyond the boundaries of the clay column. Thus as the shaft 19 is rotated the teeth at the extreme right thereof will enter the upper face of the clay column at an angle thereto, thus roughening the upper surfaces of the column along the right, longitudinal 70 corner. For the purpose of cutting the upper face of the clay column along the left longitudinal corner thereof a shaft 24 is provided, similar to the shaft 19 being placed at an angle opposite to the shaft 19 75 and journaled in bearings 25 carried by the brackets 26. This shaft is provided with a squared portion 27 and teeth 18 terminating short of the right, longitudinal corner of the clay column and extending beyond, the left 80 longitudinal corner thereof, a drive pulley 28 being provided and adapted to be driven in the direction of the arrow shown therein, thus roughening the surface of the clay column adjacent to the left longitudinal corner 85 thereof.

If desired the shafts 19 and 24 instead of extending entirely across the face of the clay column may only be of sufficient length to work upon the face of the column adjacent the longitudinal corners and for producing a brick wherein it is desired to procure a coarse textile effect upon the face this would be preferable but with the diagonal shafts extending entirely across the clay 90 column as shown in the drawings, the face of the clay column is cut at three different angles and the material is shredded or grated much finer than in the case above referred to, producing a finer textile appearance. 95

As the particles of clay which are torn and shredded by the rotary cutters are again deposited upon the face of the column of clay they will not adhere very tightly thereto and for the purpose of causing this mass to adhere firmly to the body of the clay column, a steam jet is directed thereon for the purpose of moistening the material thus ground up, causing it to adhere to the column. 100 This device consists of a steam nozzle 29 placed beyond the rotary cutters and located a short distance above the column, one end of said pipe being closed by a cap 30 and the opposite end being connected to a 105 steam line 31. Spaced apertures 32 are provided in the lower side of the steam nozzle 29 for the purpose of allowing small jets of steam to spout upon the face of the clay column. For the purpose of drying the face 110 of the column thus dampened one or more drying rolls are used. As these rolls are similar it is only thought necessary to describe the mechanism of one. Each roll is composed of a hollow metallic cylinder 33 115 provided with a cover 34 of felt or similar material. A hub 35 is located at the center of the roll and supports the roll by means of spokes 36, a shaft 37 being located through the hub 35, said shaft being mount- 120

125

ed within suitable slots 37 in each of the side frames 3 and 4 to allow the roll to always remain in contact with the face of the clay column. A "Bunsen" burner 38 enters the 5 cylinder from each side and extends to a point adjacent the spokes 36, said burners being connected to gas lines 39 provided with shut-off valves 40. As the clay column passes beneath the drying rolls the movement 10 of the column will cause the rolls to continually rotate, the heated surfaces of the rolls tending to dry the surfaces of the column. For the purpose of preventing the brick from adhering to one another when 15 they are hacked the felt covering upon the drying rolls is lubricated, the means for doing this being shown as lubricating cups 41, which are supported in any suitable manner above the rolls and so adjusted that oil will 20 continually drop upon the rolls.

As a further means for drying the face of the clay column a series of electric fans is used. In the drawings a fan 42 is shown supported above the column and adapted to 25 direct a current of air upon the face of the column for drying the same, but it will be understood that any number of fans found necessary may be used.

For the purpose of producing an effect 30 upon the side of the clay column similar to that produced upon the top face, a rotary cutter is employed and adapted to engage the side face of the column. This cutter is preferably placed at an angle as shown in 35 the drawings and consists of a shaft 43 journaled in a bearing 44 adjustably carried in a bracket 45 which is mounted upon a frame 46. The shaft 43 is provided with teeth 18 and with a driving pulley 47 adapted to be 40 rotated in the direction indicated by the arrow thereon by any suitable means. A steam nozzle 48 similar to the nozzle 29 is placed adjacent the rotary cutter just described and is adapted to direct steam upon 45 the side face of the clay column. A drying roll 49 is supported by the frames 4 and 46 and is provided with a gas burner 50.

All of the rotary cutters are rotated very 50 rapidly, about three hundred revolutions a minute having been found by experience to produce the desired result. As these cutters rotate the teeth thereon engage the face of the clay column tearing up the surface and removing a great portion of the material 55 therefrom, the portion removed being shredded and pulverized and distributed evenly upon the face from which it has been removed, and after the clay column has been acted upon by the steam jets and been cut 60 into blocks of the proper size the finished product is a brick such as shown in Fig. 7, having side and end faces, the texture of which greatly resembles a rug or carpet.

Although the drawings and above specification disclose the best mode in which I have

contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

In other devices the usual custom for securing the necessary power and motion to ornament the face of the clay column has been to depend on the power and movement of the clay column for same. In this device the source of power and motion is altogether 75 outside of the clay column; and the teeth tearing the face of the clay column are not continuously in the clay, but each engages with the surface of the clay column only momentarily and travels in the same direction 80 as the column of clay.

I claim:

1. In a device of the character described, the combination of a brick machine having a die, through which a continuous column of 90 clay is discharged, of a rotary cutter mounted above said column of clay and provided with teeth adapted to engage the face of said column of clay, a second rotary cutter located at an angle to said first named rotary cutter and means for imparting rapid 95 rotary movement to said rotary cutters.

2. In a device of the character described, the combination with a brick machine having a die through which a continuous column of clay is discharged, of a rotary cutter mounted above said column of clay, teeth provided upon said rotary cutter and adapted to engage the surface of the clay column, said teeth terminating at points intermediate the longitudinal corners of the clay column, rotary cutters located diagonally to said first named rotary cutter, teeth upon said diagonal, rotary cutters adapted to engage the surface of the clay column adjacent the longitudinal corners thereof and means for imparting rapid rotary motion to all of said rotary cutters.

3. The combination with a machine adapted to discharge a continuous column of clay 115 therefrom, of a rotary cutter adapted to remove a portion of the clay from the face of said clay column, said rotary cutter adapted to shred the material thus removed and deposit the same upon the face of the clay 120 column from which it was removed, means for moistening the face of the clay column thus treated and means for drying the moistened surface of the clay column.

4. The combination with a machine adapted to discharge a continuous column of clay therefrom, of a rotary cutter adapted to remove a portion of the clay from the face of said clay column, said rotary cutter adapted 125 to shred the material thus removed and de- 130

posit the same upon the face of the clay column from which it was removed, means for moistening the face of the clay column thus treated, and drying rolls supported in contact with the moistened surface of the clay column.

5. The combination with a machine adapted to discharge a continuous column of clay therefrom, of a rotary cutter adapted to remove a portion of the clay from the face of said clay column, said rotary cutter adapted to shred the material thus removed and deposit the same upon the face of the clay column from which it was removed, means for moistening the face of the clay column thus treated, and means for lubricating the surface of said drying rolls.

6. The combination with a machine adapted to discharge a continuous column of clay therefrom, of a rotary cutter adapted to remove a portion of the clay from the face of said clay column, said rotary cutter adapted to shred the material thus removed and deposit the same upon the face of the clay column from which it was removed, means for moistening the face of the clay column thus treated, drying rolls supported in contact with the moistened surface of the clay column, and means for directing a current of air upon the surface of the clay column thus treated.

7. The combination with a machine adapted to discharge a continuous column of clay therefrom, of a rotary cutter adapted to remove a portion of the clay from the face of said clay column, said rotary cutter adapted to shred the material thus removed and deposit the same upon the face of the clay column from which it was removed, a steam nozzle adapted to direct jets of steam upon the surface of the clay column and drying rolls supported in contact with the surface of the clay column thus treated.

8. The combination with a machine adapt-

ed to discharge a continuous column of clay therefrom of a rotary cutter adapted to shred the face of said clay column, said rotary cutter located diagonally to said clay column, means for moistening the shredded surface of the clay column and means for drying the said surface of the clay column.

9. In a device of the character described, the combination with a brick machine having a die through which a continuous column of clay is discharged, of a rotary cutter mounted above said column of clay, teeth provided upon said rotary cutter and adapted to engage the surface of the clay column, said teeth terminating at points intermediate the longitudinal corners of the clay column, rotary cutters located diagonally to said first named rotary cutter, teeth upon said diagonal, rotary cutters adapted to engage the surface of the clay column adjacent the longitudinal corners thereof, means for imparting rapid rotary motion to all of said rotary cutters, and means for adjusting said rotary cutters with relation to the surface of the clay column.

10. In a device of the character described, the combination of a brick machine having a die, through which a continuous column of clay is discharged, of a rotary cutter mounted above said column of clay and provided with teeth adapted to engage the face of said column of clay, a second rotary cutter located at an angle to said first named rotary cutter, means for imparting rapid rotary movement to said rotary cutters, and means for adjusting said rotary cutters with relation to the surface of the clay column.

In testimony that I claim the above, I have hereunto subscribed my name in the presence of two witnesses.

FRANK A. HOILES.
